UNITED STATES PATENT OFFICE.

CHARLES H. TOWNSEND, OF BERKELEY, CALIFORNIA.

CONCENTRATING LAMP-SHADE.

1,104,330.

Specification of Letters Patent.

Patented July 21, 1914.

Application filed January 26, 1914. Serial No. 814,317.

To all whom it may concern:

Be it known that I, CHARLES H. TOWNSEND, a citizen of the United States, residing at Berkeley, in the county of Alameda, 5 and State of California, have invented new and useful Improvements in Concentrating Lamp-Shades, of which the following is a specification.

My invention relates to improvements 10 which are intended especially for use with reflecting lamps, such as those of locomotives, automobiles and motorcycles, and generally where a powerful light is thrown in one direction by means of a reflector.

15 My invention consists in applying to such lamps a semi-conical or equivalent reflector, hinged above and capable of being dropped so as to reflect that portion of the light which is ordinarily thrown upward into 20 the air and wasted, and concentrating such light directly upon the road or path in front to be illuminated.

It also comprises a means for conveniently raising and lowering such reflector 25 about a superposed hinge and a means for retaining the reflector in either its lowered or raised position.

It also comprises details of construction which will be more fully explained by reference to the accompanying drawings, in which—

Figure 1 illustrates my invention, showing the reflecting hood thrown down into its normal position and thrown upward in 35 dotted lines. Fig. 2 shows the application of such a hood in permanent position. Fig. 3 is a side elevation of Fig. 1. Fig. 4 is a detail perspective view of the hinge and crank arm.

40 For use of automobiles and like vehicles, a powerful light is usually fixed at the front having a reflector or reflectors which concentrate the light ahead upon the road, but the great portion of the light will also be thrown upward and wasted in the air.

It is the object of my invention to prevent this waste, and to particularly protect the eyes of the driver from such upwardly thrown light, and to increase the effectiveness of the light by throwing a greater portion of it forward, with sufficient light upon the road just in front of the machine to illuminate the road.

55 In the present drawings I have only shown the front portion of the lamp, having the usual or any suitable reflector and

transparent front through which the light is thrown.

A represents such a lamp, and 2 is a reflecting hood, which is preferably made of a semi-conical form at the front, as at 3, and may have a semi-cylindrical rim, as at 4. This rim is suitably supported by a bracket 5 and sleeve-surrounded posts 6 which pass through the bracket; the sleeves serving to fix the distance between the bracket and the rim of the reflector, and the posts passing through said rim and being secured by nuts or equivalent fastenings. The rear portion of the bracket has one portion of a hinge, 70 as shown at 7, the remaining portion being secured to the fixed rim of the lamp by bolts, as shown at 8. The reflector and bracket are thus made turnable about the hinge and in ordinary use may be dropped down 75 to a horizontal position, in which the light thrown out by the reflector from the lower part of the lamp front will be distributed in the usual way along the line of the road in front. That portion which is thrown upward will be reflected by the interior of the conical reflector 2 and will be thrown downwardly and forward, no rays being allowed to escape upwardly and be dispersed into the atmosphere where they would be of no 80 use and would blind the driver or others approaching from the opposite direction. In order to open this reflector, if desired, I have shown an arm 11 fixed to the bracket 5 and it may be provided with a cord, wire 85 or other attachment by which the reflector can be thrown upwardly at right angles to its normal position, thus exposing the whole front of the lamp.

It will be understood that under certain 90 conditions and for economy the device may be constructed, as shown in Fig. 2, so as to remain permanently in position.

In order to retain the reflector in either position, I have shown a sufficiently strong 100 spring having a tension sufficient to hold the reflector down, or up when it is thrown upward, but not sufficient to prevent the reflector from dropping by gravitation when it is released. This spring is attached to an arm 105 9 which extends backwardly from the hinge and above the lamp rim, and the rear end of the spring is mounted upon a roller 10, turnable upon the crank arm, thus allowing the spring, the front end of which is attached to 110 the reflector, to assume a point below the crank arm and enabling it to pull the reflec-

tor into its dropped position, or, when turned upwardly, the pull will be behind the hinge and arm, thus acting to hold the reflector open. By this construction I am enabled to efficiently control the direction of the light, and to greatly improve its power as well as to shield the eyes of the driver or of other persons meeting the car.

Having thus described my invention, what I claim and desire to secure by Letters Patent is—

1. The combination with a reflecting and like lamp, of a segmental rim concentric with the axis of the lamp, a conical reflector converging forwardly therefrom, a hinge, one leaf of which is fixed to the top and front of the lamp frame, the other member turnable thereon and extending forwardly, sleeves extending between said member and the top of the reflector rim, and bolts extending through said sleeves to secure the reflector to the hinge.
2. A reflecting lamp of the character described, a semicircular rim concentric with the axis of the lamp, a convergent reflecting surface extending from said rim, a hinge, one member of which is secured to the top of the lamp and the other member to the rim of the reflector, an arm fixed to said latter member and capable of movement to raise or lower the reflector about the hinge, and a spring having one end fixed to the front of the reflector rim and the other at a

point so related to the hinge axis that it will exert a pull to hold the reflector either open or closed.

3. The combination with a reflector of the character described, of a concentric semicircular rim having a semicircular, semi-conical reflecting segment extending forwardly therefrom, a horizontal hinge, one member of which is secured to the front of the lamp and the other to the reflector rim, an arm by which the reflector may be turnably moved about the hinge to open or close it, a crank arm extending out of line with the axis of the hinge, and a roller turnable upon the outer end of said arm, and a spring having one end connected with said turnable roller and the other to the front of the lamp rim and capable of exerting a pull to retain the reflector either open or closed.

4. In combination with a reflecting lamp, a supplemental reflector hinged thereto, an eccentric member connected to the hinge pin, and a spring connected to said member and the supplemental reflector whereby the latter is positively held by the spring in either operative or inoperative position.

In testimony whereof I have hereunto set my hand in the presence of two subscribing witnesses.

CHARLES H. TOWNSEND.
